UNITED STATES PATENT OFFICE.

ROBERT M. PIERSON, OF AKRON, OHIO, ASSIGNOR TO THE B. F. GOODRICH COMPANY, OF NEW YORK, N. Y., A CORPORATION OF NEW YORK.

FLUSH-TANK VALVE.

Application filed January 11, 1927. Serial No. 160,400.

This invention relates to buoyant rubber valves for flush tanks, and it consists in a novel construction of flexible-edge valve calculated to promote an effective seating in a 5 large variety of sizes and shapes of tank outlets, to prevent permanent deformation or pulling out of shape and at the same time to preserve an adequate air-chamber and avoid the retention of substantial 10 amounts of water on the upper side of the valve when it is floating, so that the valve may remain unseated until the tank is fully discharged.

The accompanying drawing is a vertical 15 sectional view, partly in elevation, showing a preferred form of my invention.

The body of the tank valve is integral or unitary, being made of resilient, vulcanized rubber composition and is preferably of the 20 full-molded type, vulcanized in an outer mold upon a metal core adapted to be withdrawn through a relatively-large opening in the bottom of the valve.

The valve body as here shown comprises 25 three principal members, namely an upper or roof member 1 of conoidal shape, centrally of which is embedded the metallic lifting spud 2 in a short stem 3, although the stem as a distinct element is not essential; a relatively-shallow, annular, thin-walled intermediate member 4 depending 30 from the outer edge of said upper member 1, and a lower or seating member 5 having an opening 6 at the bottom thereof for withdrawing the molding core which forms the 35 internal air-chamber 7.

The upper member 1 is relatively thick-walled in order to impart a desirable degree 40 of stiffness to the top of the valve in both radial and vertical directions, and its conoidal shape contributes to the vertical stiffness without requiring an excessive amount of rubber.

The lower or seating member 5 may have 45 a generally convex or conoidal shape, tapering downwardly from its upper or greatest diameter, and I prefer to curve the lower part of its profile on a shorter radius than the upper part, but the particular shape of 50 said profile is subject to some variation. The lower part of said member 5 is relatively thin-walled to promote good sealing against the valve seat, and the thickness gradually increases through the upper marginal part 55 to a maximum at the upper end thereof, the

effect of such thickening being to increase the life of the rubber and prevent the seating portion from taking a permanent set or being pulled out of round to an objectionable extent.

The member 4, whose shape and disposition might be varied somewhat without departing from my invention, is preferably made of solid rubber and constitutes a means for permitting local flexure of the thickened 60 upper edge or margin of the seating member 5 without substantial radial resistance from the relatively-thick and hence relatively-stiff upper or roof member 1, thereby allowing the valve to seat properly in a wide 65 outlet or one of slightly irregular shape, or when the valve is slightly cocked or misaligned in its seat. The height of member 4 is a small fraction only of the diameter of member 1, so that the latter substantially 70 resists any extreme flexure of the upper edge of the seating member 5.

Being, as here shown, substantially vertical, member 4 opposes a vertical compressive 75 resistance to deformation of the valve due to the hydrostatic head of water exerted upon member 1 and also a vertical tension resistance transmitting the pull of member 1 directly to member 5 without undue lost motion when the valve is being lifted off its seat.

The upper marginal surface of the seating member 5 forms a substantially-horizontal narrow ledge 8 which can not retain an appreciable amount of water adding to the 80 weight of the valve when the latter floats, and hence the valve will tend to remain open until the tank is fully discharged during a flushing operation.

The above combination of features provides a valve of maximum resiliency in its seating portion, having an adequate air-chamber and high degree of buoyancy, using a minimum amount of rubber, with sufficient stiffness to avoid pulling out of shape, and having a structure which, notwithstanding the relative stiffness of its upper member and the position of its margin with respect to the greatest diameter of the valve, provides a high degree of flexibility in the upper edge 90 portion of the seating member, which produces good seating in a wide variety of shapes and sizes of outlets, under the conditions encountered in service.

I claim:

110

1. A flush-tank valve of resilient rubber composition including a lower or seating member which is relatively thickened annularly thereof in its upper marginal portion, 5 an upper or roof member, and an intermediate, relatively thin and flexible annular member, the height of which is a small fraction only of the diameter of said upper member, connecting the outer edge of said upper member with the thickened margin of the lower member, within the outer periphery of the latter.
- 10 2. A flush-tank valve of integral, resilient rubber composition including a thickened, upper or roof member, substantially in the form of a cone with its apex uppermost, a relatively shallow, thin and flexible,

annular intermediate member depending from the outer edge of said upper member, and a lower or seating member whose upper margin is connected with the lower edge of said intermediate member, the top surface of the lower member forming a ledge between its outer periphery and said intermediate member.

20 25 3. A flush-tank valve according to claim 2 in which the wall of the seating member is relatively-thick in its upper portion and tapers to a smaller thickness in the lower portion thereof.

30 In witness whereof I have hereunto set my hand this 7th day of January, 1927.

ROBERT M. PIERSON.
